UNITED STATES PATENT OFFICE.

CHARLES WILLIAM GREEN, OF PEORIA, ILLINOIS.

INTERNAL-COMBUSTION ENGINE.

1,295,026.

Specification of Letters Patent. Patented Feb. 18, 1919.

Application filed February 9, 1916. Serial No. 77,122.

To all whom it may concern:

Be it known that I, CHARLES WILLIAM GREEN, a citizen of the United States, and a resident of Peoria, in the county of Peoria and State of Illinois, have invented certain new and useful Improvements in Internal-Combustion Engines, of which the following is a full, clear, and exact description, reference being had to the accompanying drawing, forming part of this specification.

My invention relates to internal combustion engines of the silent type wherein the puppet valves of the ordinary engine are replaced by flat slide valves, and wherein should the slide valves become worn and permit a leakage from the combustion chamber, suitable means are provided whereby the valves may be properly re-adjusted.

The object of my invention is to provide a simple and compact valve mechanism and also a simple and efficient adjusting means for the valves.

A further object is to so arrange the cylinders and associated parts that the same may be easily machined and readily adjusted should occasion require.

Further objects of my invention will appear herein and be described as the specification proceeds.

The novelty of my invention will be hereinafter more fully set forth and specifically pointed out in the claims.

In the accompanying drawing,

Figure 1 is a sectional elevation through a cylinder showing the ordinary parts of an internal combustion engine and also showing my valves, their operating connections, and the means for adjustment.

Fig. 2 is a side elevation partly in section of the upper part of Fig. 1.

Fig. 3 is a sectional plan view of Fig. 1 taken through the ports.

The same numerals of reference are used to indicate identical parts in all the figures.

I am aware that there are a number of patents now in force and covering various forms of slide valves as applied to internal combustion engines, and I therefore disclaim the broad idea of a slide valve.

My present invention is as applicable to multi-cylinder engines as it is to single cylinder, and I will confine myself to a description of a single cylinder, it being understood that a multi-cylinder engine only re-

quires a duplication of the parts described for each cylinder, and where my invention is applied to a multi-cylinder engine, such engine may have its cylinders arranged 60 separately or *en bloc*.

Referring to the drawings, 1 represents any suitable crank case within which is journaled the crank shaft 2 after the usual or suitable form of construction. The 65 lower end of the connecting rod 3 is connected to the piston 4, which latter reciprocates in the cylinder 5, which is suitably attached to the crank case 1.

The cylinder 5 is provided near its upper end with inlet and exhaust ports 6 and 7, and these ports extend from the combustion chamber and terminate at the valve seats 8. The valve seats 8 are flat surfaces arranged vertically on opposite sides of the 75 cylinder as will be readily seen by reference to Figs. 1 and 3.

Attached to the surfaces 8, as by means of cap-screws 9, (Fig. 2), and one on each of said surfaces, are valve housings 10 between the inner faces of which and the valve surfaces 8 are confined the valves 11. There are two of such valves on each side of the cylinder, and each of the valves is provided with a port 12 located near its upper end and 85 a bifurcated enlargement at its lower end to receive the upper end of a connecting rod 13 by means of which the valve is operated.

The connecting rods 13 are attached, at their lower ends to a suitable eccentric shaft 90 14 which is journaled in the crank case and driven at half the speed of the crank shaft and from the crank shaft by means of the usual or any suitable driving connection which, forming no part of my present invention and being common to all forms of 95 internal combustion engines, is not shown.

It is to be understood that there are two eccentric shafts and that each shaft has two eccentricities thereon and opposite the bifurcated ends of the valves, in such position that when the connecting rods are connected to both the eccentric and the valve and the shaft rotated, an up and down motion will be imparted to the valves to open and close 105 the ports to permit ingress of the combustible charge on the inlet side of the engine and egress of the burned gases at the exhaust side thereof.

Carried by the inner face of the valve 110 housings 10 and bearing against the outer face of the outer valve 11 is an adjusting de-

vice which consists of a wedge 15, vertically adjustable as by means of the screws 16. The wedge 15, when properly adjusted, serves to maintain the valves in proper working relation to the surfaces 8.

Should the valves become worn from constant service and not properly fill the space between the wedge and the valve surface it is only necessary to remove the hand-hole 10 cover 17 whereupon the lower ends of the valves and their operating mechanism are exposed and then by means of the adjusting screws, elevate the wedge or compensating device to a position where the valves 15 are again brought into proper contact with the valve surface, after which the wedge is locked against upward or downward movement as by means of the set-screws 18.

It is to be observed that the valve housing 20 10 is ported in line with the cylinder ports and that a raised surface 19 is provided for suitable attachment of a manifold which extends to the carburetor on the inlet side and to the exhaust pipe on the exhaust side. 25 In multi-cylinder engines the manifolds last referred to may if desired be made integral with the valve housing, which latter may be continuous over all the cylinders.

It is to be observed that the machine work 30 on the cylinder itself where the valve surfaces are is exceedingly simple, and consists in either grinding or milling the perfectly flat surface on each side of the cylinder against which the flat surface of the 35 valves operates and against which the valve housings are suitably bolted as before referred to. Similarly the valves themselves are constructed of thin plates which are very easily machined to the necessary accuracy,

and in fact all of the valve parts are produced by simple straight surface work.

In assembling, it is not necessary to resort to the extreme accuracy required for other forms of engines for the reason that the compensating device will accommodate variations in the machine work as well as adjust the valves after they have become worn, it being borne in mind that the great difficulty surrounding the operation of internal combustion motors is to prevent leakage at the 50 valves.

Having thus fully described my invention, I claim,

1. In an internal combustion engine, the combination of a cylinder, ports, a pair of sliding valves operating over said ports, a housing over said valves, a wedge between said housing and said valves whereby the latter may be adjusted, means for adjusting said wedge to compensate the wear of said valves, means for locking said adjustment, and a cover over said locking means whereby when said cover is in place the adjustment of said wedge can not be changed.

2. In an internal combustion engine, the combination of a cylinder, an inlet port, an exhaust port opposite said inlet port, a pair of sliding valves operating over each of said ports, a housing over each of said pair of valves, a wedge between each housing and its pair of valves, means for adjusting said wedges to compensate for wear of said valves, means for locking said wedges in their adjusted positions, and covers over said locking means whereby when said covers are attached said wedges can not be moved.

CHARLES WILLIAM GREEN.
